United States Patent Office

Des. 181,773
Patented Dec. 17, 1957

181,773

DESK PEN SUPPORT OR THE LIKE

Clarence Zierhut, Los Angeles, Calif., assignor to Paper Mate Manufacturing Company, Culver City, Calif., a corporation of Delaware

Application March 4, 1957, Serial No. 45,099

Term of patent 14 years

(Cl. D74—1)

Fig. 1 is a view in perspective of a desk pen support embodying my new design;

Fig. 2 is a plan view thereof;

Fig. 3 is a side elevation thereof;

Fig. 4 is a rear elevation thereof; and

Fig. 5 is a view in section therethrough.

The broken line showing of a pen in Fig. 1 is for illustrative purposes only.

I claim:

The ornamental design for a desk pen support or the like, substantially as shown and described.
